(Cl. D3—9)

Fig. 3

To all whom it may concern:

Be it known that I Gertrude M. R. Smith, a citizen of the United States of America and a resident of the city of Detroit, county of Wayne, State of Michigan, have invented a new, original, and ornamental design for a Sleeping Pillow, of which the following is a specification, reference being had to the accompanying drawings, forming a part hereof, in which:

Fig. 1 is a perspective view of a sleeping pillow incorporating my new design;

Fig. 2 is a plan view of my pillow;

Fig. 3 is a side elevational view thereof.

I claim:

The ornamental design for a sleeping pillow, as shown.
